UNITED STATES PATENT OFFICE.

FRANK KUHN AND JAY A. HAND, OF DETROIT, MICHIGAN, ASSIGNEES TO AMERICAN ELECTRICAL HEATER COMPANY, OF DETROIT, MICHIGAN, A CORPORATION OF MICHIGAN.

ELECTRICAL HEATER.

1,419,935.

Specification of Letters Patent. Patented June 20, 1922.

Application filed June 15, 1918. Serial No. 240,149.

To all whom it may concern:

Be it known that we, FRANK KUHN and JAY A. HAND, citizens of the United States of America, residing at Detroit, in the county of Wayne and State of Michigan, have invented certain new and useful Improvements in Electrical Heaters, of which the following is a specification, reference being had therein to the accompanying drawings.

10 This invention relates to luminous electric heaters and more particularly to electric heaters of the type in which a heating element is mounted substantially at the focus of a concave reflector.

15 The invention consists in various structural features, including the employment of a common means for detachably holding the reflector upon its support and for detachably mounting a guard in front of the heating

20 unit, the establishment of a connection between the heater and its supporting standard such that any desired direction may be given to the radiant heat, the mounting of a plurality of these heaters upon a common

25 standard, and making provision for independent adjustment thereof with relation to said standard, and providing for the establishment of the electrical connections and for a location for said connections within the

30 standard, such as to facilitate the assembly and repair of the heater.

In the accompanying drawings:

Figure 1 is a front view of the heater;

35 Figure 1^a is a top view of the heater illustrating the relative adjustability of the duplicate heating devices;

40 Figure 2 is a vertical sectional view taken on line 2—2 of Figure 1, showing the provision of establishing the electrical connections within the standard;

Figure 3 is a sectional view taken on line 3—3 of Figure 2, showing the pivotal connection of the heater supporting arms with the standard;

45 Figure 4 is a section taken on line 4—4 of Figure 1, showing the mounting of one of the heating units and its reflector upon a support;

Figure 5 is a rear view of one side of the 50 heater.

Figure 6 is a perspective view showing in disassembled relation the adjoining portion of the standard and one of the arms which

support the heating devices, the slotted plate used in connecting said parts being also illustrated in this view.

In these views the reference character 1 designates a base, and 2 a hollow standard centrally rising from said base. Upon the upper portion of said standard there is 60 mounted a pair of duplicate heaters one at each side of the standard, each comprising a bifurcated arm 3 pivotally engaging the standard, the pivotal axes of said arms being in alignment, a dished head pivotally carried 65 at the outer end of each of said arms, a socket member 5 disposed within each of said heads, a heating unit 6 detachably engaging each socket member, and a reflector 7 secured to each of said heads and having said 70 heating unit arranged at substantially the focus thereof. Preferably said reflectors are of an ellipsoidal shape so that their reflected rays may be brought to a focus at a predetermined point in front of said reflector.

75 Each of the heating units 6 comprises an insulating core 8 having a resistor 9 wound thereupon, said core being mounted upon a bolt 10 which is engaged with a bracket 11, said bracket having a pair of contact pins 12 80 projecting therefrom with which the terminals of said resistor respectively have electrical connection.

85 Each socket member 5 comprises an insulating body 13 wherein is embedded a pair of sockets 14 within which the pins 12 may be detachably inserted. The socket member is centrally located within the head 4 in a spaced relation to the wall thereof and is secured to said head by the bolts 15. An annular series of apertures 16 is formed in each head 4 in communication with the space between said head and the socket member, thus providing for a circulation of air through the head.

95 The pivotal joint between each head 4 and the corresponding arm 3 is established by forming upon the head a pair of lugs 17, which project between the furcations of the adjacent arms and are pivoted respectively 100 thereto by bolts 18. The inner ends of these bolts engage disc-shaped nuts 19 which clamp the lugs 17 against the furcations of the arm 3 with sufficient pressure to maintain the head 4 fixed in various positions of angular adjustment. The rotation of the nuts 19

is prevented by peripherally forming the same with lugs 20 which are bent at a right angle and inserted in apertures in the furcations of the arm. The angular movement of 5 each head 4 is limited by forming the lugs 17 thereof with projections 21, which coact with the lugs 20 to form stops.

To pivotally mount each arm 3 upon the standard 2, registering apertures 22 are 10 formed in each arm and the adjacent wall of the standard and within said apertures there is inserted a collar 23 having a flange 24 bearing upon the arm and formed with an annular groove 25 which is engaged by a 15 locking plate 26 within the standard, said plate being slotted, as indicated at 27, to fit said groove. Said plate is bowed and is formed of resilient material so that when it is forced downwardly to engage the slot 27 20 with the groove 25, an axial stress will be exerted upon the collar 23 and through said collar upon a corresponding arm 3 causing the latter to engage the standard with sufficient pressure to maintain it fixed in various 25 positions of angular adjustment. The apertures 22 of the standard are formed with spaced radial shoulders 28, which shoulders are engageable by a lug 29 projecting from the adjacent arm 3 to limit the permissible 30 limited movement of the arm. Preferably the rotation of the arm 3 will be limited to an arc of ninety degrees, that is to say between positions corresponding to a forwardly directed and an upwardly directed position of 35 the reflector.

The rear wall 30 of the standard 2 is detachably held in place by screws 31, and said wall carries upon its lower portion a socket member 32 which is located within the standard 40 when the heater is assembled. Within said socket is arranged a pair of contact pins 32^a which may be detachably engaged by a plug (not shown). The pins 32^a respectively have an electrical connection with a pair of 45 binding posts 33 with which conductors 34 are engaged within the standard, said conductors extending to the upper portion of the standard and there passing through the collars 23 and between the furcations of the 50 arms 3 to the respective heads 4.

The standard 2 is surmounted by a detachable cap 35, the front and rear walls of said cap and standard being formed with registering slots 36 through which are passed 55 the bent lower ends 37 of a handle member 38, whereby the cap is held in place upon the standard. The resiliency of the handle member serves to permit engagement and disengagement of its extremities 37 from said 60 slots.

The heads 4 are respectively formed with annular flanges 39 at their edges against which the reflectors are respectively seated. With each of said flanges there are engaged 65 the inner extremities of a plurality of arms

40, which extend adjacent the exterior faces of the reflectors to the rims thereof and are hooked, as indicated at 41, to engage with said rims. Outside of said hooks each of the arms 40 is return-bent to form reversed 70 hooks 42, the hooks 42 serving to retain wire guard members 43 positioned centrally at the front of the reflectors. The axes of the pivotal connections between each arm 3 and the standard 2 and corresponding head 4 are 75 in transverse relation so that the two said pivotal connections coact to secure the effect of a universal joint permitting the direction of the radiant heat to be varied through a wide range. Also by swinging the heads 4 80 slightly toward each other about their connections with the arms 3, the radiant heat emanating from both heating units may be concentrated in an area not far from the heater. It is to be noted that the arms 40 perform the dual function of retaining the reflectors in proper relation to the heating units and retaining the guard in proper relation both to the heating units and reflectors. The reflectors are each formed with an aperture 85 at their centers of a diameter somewhat greater than that of the heating units so that after the fastening devices have been released, the reflectors may be removed without disturbing the heating units. The ready detachability of the reflectors is an important feature since it permits of the reflectors being stored in a nested relation to each other separate from the heaters and being quickly applied to the heaters when the 90 latter are ready for use. By mounting the socket member 32 with its terminals 33 upon a removable wall 30 of the standard, it becomes possible to engage the conductors 34 with said terminals without the workmen 95 being hampered for lack of room and after the connections have been established, the conductors may be thrust into the standard as the wall 30 is being shifted to its proper 100 relation to the standard.

What we claim as our invention, is:

1. The combination with a support and an electric heating device, of an arm having its extremities respectively pivotally connected to said heating device and support, the axes 110 of said pivotal connections being transverse to each other, and means creating frictional resistance at each of said joints to hold the parts adjusted in various angular relations.

2. An electric heater comprising a stand- 115 ard, a heating device, an arm supporting said heating device, an annularly grooved collar mounted in registering apertures of said arm and standard, said collar having a portion bearing upon the arm to hold the 120 same against the standard, and a member interior to the standard formed with a slot engaging the annular groove of said collar, said member being bowed to subject said 125 collar to an axial stress, whereby said arm 130

is held firmly engaged with said standard to resist relative rotation.

3. An electric heater comprising a support, a heating device, an arm having its extremities respectively pivotally connected to said heating device and support, the pivotal axes being substantially transverse, and

means limiting relative angular movement at each of said pivotal connections.

In testimony whereof we affix our signatures.

FRANK KUHN.
JAY A. HAND.
